2 Claims. (Cl. 158—36.3)

This invention relates to oil burning installations for furnaces of the kind wherein oil is supplied to the burner by suitable pumping means and the operational range of the burner is controlled by providing means for bypassing surplus quantities of oil at a point upstream of the burner discharge orifice. Accordingly in operating such installations, when the burner is to operate at maximum output the by-pass will be closed so that the whole of the oil will be injected into the furnace, but when it is desired to operate at a lower rating, the by-pass will be opened to permit a controlled quantity of oil to be bypassed. The burners of this kind are generally known as "spill" type burners.

In order that the oil reaching the burner has the requisite viscosity to ensure efficient atomisation, it is known to provide a heating device in the oil flow line and to provide high and lower pressure pumps for feeding the oil to the burner. Hitherto a major difficulty of operating oil burning installations of this kind has been arranging for the satisfactory disposal of the hot by-passed oil, and it is an object of the present invention to provide means whereby this oil is safely disposed of in a manner that will improve the overall efficiency of the installation.

According to the present invention an oil burning installation for a furnace having spill type burners comprises a pump connected in the oil flow line for delivering oil to oil heating means, a second pump operating at a higher pressure than the first for delivering oil discharged from the heater to the oil burners of the furnace and means for collecting the spilled oil by-passed from the burners as surplus to requirements and delivering it into the oil flow line at a point intermediate the heater and the first mentioned pump.

By this arrangement the hot spilled oil is recirculated to the oil system and its heat is accordingly conserved thereby enabling the heating device to operate with less input heat than would otherwise be the case.

The heating device may be in the form of a heat exchanger including concentric flow passages through which steam and oil to be heated are caused to flow. A temperature control device is provided at the infeed of the heat exchanger to control the supply of heating steam in accordance with the oil temperature it is desired to maintain at the outfeed of the heater or at the entry to the burner so as to ensure that when it reaches the atomising nozzle of the burner it will be at a suitable temperature and viscosity for efficient atomisation.

To enable the invention to be fully understood it will now be described with reference to the accompanying drawing, which illustrates in diagrammatic form an oil burning installation according to one embodiment of the invention.

As shown in the accompanying drawing, an oil burning

2

installation includes a low pressure pump 1 having its inlet connected to a pipe 2 connected to a storage tank (not shown) containing oil which will normally be at a relatively low temperature. As shown a strainer 3 is provided in the pipe 2. The discharge side of the pump 1 is connected with a pipe 4 leading to a mixing chamber 5 whose discharge side is connected to a pipe leading to the infeeds of a pair of heat exchangers 6. Each heat exchanger includes oil passages 7, 7a and steam passages 8, 8a, the steam passages having inlets 9 and an outlet 10. As shown in the drawing, the mixing chamber is an enlarged right cylinder with its axis mounted in a vertical plane. The cold oil inlet pipe 4 connects to the center of the bottom of chamber 5.

15 The oil discharged from the heat exchangers flows through a pipe 12 and filter 12a to a pump 13 which is adapted to operate at a higher pressure than the pump 1 and deliver the heated oil through the pipe 14 to the burners 15 of the furnace. A by-pass conduit 16 is provided for each burner and is connected with a main by-pass pipe 17 leading to the mixing chamber 5. The operational range of the burners is controlled by adjusting a regulator valve 18 in the by-pass pipe 17 so as to vary the amount of oil by-passed from the burners.

20 25 Spilled oil surplus to requirements of the burners passes through the conduits 16 and by-pass 17, to the mixing chamber 5 where it is recirculated through the oil system by mixing with the relatively cold oil being pumped by the pump 1. The temperature of this oil is thus raised by the hot spilled oil and the mixed oil then flows to the infeed of the heat exchangers 6.

The hot spilled oil is delivered into the mixing chamber 5 adjacent to its lower or inlet end, through nozzles 19 adapted to inject the oil in streams tangentially to the flow 30 35 path of the cold oil delivered by the pump 1.

It will be understood that the pressure in the mixing chamber will always be less than that of the oil being spilled from the burners in order to ensure that the spilled oil will readily flow into the chamber irrespective of the 40 quantity spilled. It is noted that low pressure pump 1 supplies oil to an enlarged cylindrical mixing chamber 5 and that a high pressure pump 13 supplies oil under high pressure to the burners 15. The pressure in the bypass 17 is maintained by oil from the high pressure pump 13 fed through the spillway in the burners. Preferably the arrangement is such that the pressure in the mixing chamber is at a minimum when the rate of spill registers its maximum, that is, at periods when the burners are operating at low demand.

45 It is desirable to maintain a substantially constant pressure, adequate to prevent vaporisation of the oil, at the inlet side of the high pressure pump 13 and to ensure this a by-pass pipe 20 is connected between the discharge and inlet sides of the low pressure pump 1, a pressure responsive valve 21 being provided which is arranged to open automatically if the pressure at the suction side of the high pressure pump 13 exceeds a predetermined figure, for example 10 lbs. above atmospheric pressure. As shown the valve 21 has a diaphragm disposed in a diaphragm chamber 22, one side of the diaphragm being connected by a pipe 23, to the suction side of the pump 13 and the other being connected to atmosphere by a pipe 23a so that when the pressure at the suction side of the pump 13 exceeds the predetermined figure, for example 10 lbs. above atmospheric pressure, the diaphragm will be actuated to open the valve 21.

50 55 60 It will be noted that the pipe 23 is connected in the

flow line to pump 13 downstream of the filter 12a and accordingly the pressure at the suction side of the pump 13 can be accurately controlled and will not be affected by the condition, for example choking up, of the filter.

To prevent damage to the high pressure pump in the event that for some reason the burner valves are not open when the installation is operating, a by-pass 24, including a pressure relief valve 25, is provided between the discharge and inlet sides of the high pressure pump 13. This valve is, however, only a safety device and under normal conditions it will remain closed. A by-pass 31 having a relief valve 32 is also provided connecting the inlet and outlet sides of the low pressure pump 1.

The pumps 1 and 13 are designed to run at constant speeds and as shown are driven through suitable gearing by a common prime mover 26 such as a steam turbine through shafts 36 and 38. If desired, however, each pump may be independently driven.

When the burners are required to operate at light load, instead of all the burners remaining in operation, any desired number can be completely shut down by the valves 14a, 17a and for example only two burners left in use. In this case the supply of oil would be curtailed by running the pumps 1, 13 at reduced speed, no adjustment of the heaters being required. When both pumps are driven by a common prime mover, the control of the latter would automatically effect a simultaneous and equal reduction in the speed of both pumps.

The temperature of the heat exchangers 6 is adapted to be adjusted to ensure that the oil will be at a temperature such as to ensure efficient atomisation when it reaches the burners.

According to one form of temperature control, the steam inlets 9 of the heat exchangers 6 are connected to a common steam supply line 9a which has a valve A which is connected with a heat responsive element or device B located in the flow line 14. The arrangement is such that the supply of heating steam to the exchangers 6 is automatically controlled in accordance with the temperature of the oil discharged from the heat exchangers.

If desired either of the heat exchangers 6 may be shut down by closing the respective oil inlet and discharge valves 6a, 6b and the appropriate steam inlet valve 9b. It will be noted that the arrangement of the temperature control is such that the valve A will operate to control the flow of heating steam irrespective as to whether one or both heat exchangers are in use.

By this means when the burner is operating under light load and a relatively large quantity of hot spill oil is being by-passed and mixed with the incoming cold oil, the supply of heating steam to the heat exchangers can be greatly reduced without impairing the efficiency of the installation.

An important advantage of the invention is that the hot spill oil is safely disposed of and the danger of fire or explosion which might result if the hot oil were returned to the fuel tank, is entirely eliminated.

A further advantage is that, by adjustment of the setting of the oil temperature control according to the grade of oil being consumed, the viscosity and pressure of the oil supplied to the high pressure pump 13 will remain unaltered regardless of its viscosity as it is being drawn from the storage tank. In consequence the pressure characterised at the output of this pump will be unaffected by the grade and temperature of the oil entering the low pressure pump 1, whether it be the normally used heavy boiler oil or any lighter and less viscous oil.

An important advantage of positioning the heater between the low and high pressure pumps is that the heater may be designed to operate at the low pressure of the oil being supplied by the low pressure pump. An advantage of positioning the filter 12a between the pumps 1, 13 is that the pressure in the filter cannot exceed that of the pump 1, as the relief valve 32 will automatically open if the back pressure due to the filter becomes excessive.

By maintaining constant viscosity and pressure of the fuel at the inlet of the high pressure pump 13 and selecting suitable pressure-output characteristics at the outlet side of this pump, correct burner inlet pressure is assured for any desired burner output by adjustment of the single regulator valve 18 which controls the rate at which spilled oil flows through the by-pass 17. The provision of additional valves to control the flow of oil to the burners is accordingly obviated.

10 The regulator valve 18 may be operated by remote control from an instrument panel.

It will be understood that any desired number of burners may be included in the installation, each burner being connected to the oil flow line leading from the high pressure pump and connected with a by-pass conduit 16 at a point upstream of their discharge orifices.

15 The pumps 1 and 13 may be of any convenient type and the heat exchanger may take other forms than that shown.

20 The installation may be made adaptable for various grades of fuel oil and to this end one or more valve controlled connections, such as 28 may be provided for the flow line on the suction side of the pump 1. For example a diesel oil supply pipe may be connected to the connection 28 and the supply to the pipe 2 shut off by closing the valve 29 and the diesel supply opened by opening the valve 30.

25 The invention is particularly adapted for oil burning furnace installations for marine propulsion plant.

30 I claim:

1. In an oil burning installation for a furnace including a plurality of spill type burners, an oil flow line connected with the supply side of the burners, a heater in said flow line, a mixing chamber connected in said flow line upstream of said heater, a low pressure pump for delivering oil fuel through said chamber to the heater, a by-pass conduit connecting the downstream side of each of said burners with said mixing chamber, a high pressure pump connected in the flow line between the heater and the supply side of the burners for delivering the heated oil to the burners, said mixing chamber comprising a cylindrical member, an axially disposed inlet port in the bottom thereof communicating with said low pressure pump for supplying oil at a relatively low temperature, 35 annularly disposed nozzle means mounted in the lower portion of said cylindrical member and connected to said bypass conduit and directed to inject oil in streams tangentially of the flow path of the oil delivered from said low pressure pump, the pressure in said mixing chamber being maintained less than that of the oil being spilled from said burners by the combination of high and low pressure pumps, and means for regulating the operation of said burners comprising a single valve in said by-pass conduit for regulating the amount of oil by-passed from said burners into the said mixing chamber.

40 2. An oil burning installation for a furnace having a series of spill type burners, comprising an oil flow line connected with the supply side of the burners, a heater in said flow line, a low pressure pump for delivering oil to the heater, a mixing chamber connected in said flow line between said heater and said low pressure pump, a common by-pass conduit for receiving hot oil spilled over from all said burners and delivering it into said mixing chamber, a high pressure pump connected in the flow line between the heater and the supply side of the burners for supplying oil heated by said heater to said burners, means for automatically controlling the heater to ensure that the oil discharged therefrom will be at a predetermined constant temperature, said mixing chamber including a cylindrical member, an inlet portion axially disposed in the bottom of the cylindrical member and connected to said low pressure pump, nozzle means positioned within the lower end of said cylindrical member and connected to said bypass for delivering hot oil spilled from said burners to the lower end of said cylindrical

member whereby said hot oil is directed through said nozzle means, the pressure in said mixing chamber being maintained less than that of the oil being spilled from said burners by the combination of high and low pressure pumps, and means for controlling the operation of 5 said burners comprising a single valve in said by-pass conduit operable to regulate the amount of hot spilled oil permitted to flow into said by-pass conduit.
